UNITED STATES PATENT OFFICE.

THEODORE WILLARD CASE, OF AUBURN, NEW YORK.

ELECTRICAL APPARATUS.

Application filed April 16, 1923. Serial No. 632,496.

- This invention relates to a new and improved electrical apparatus, particularly adapted for translating sound waves into light waves or variations of light waves which can be efficiently photographed or reproduced upon a film, thereby constituting a translatable film record of sound waves, particularly articulate or musical sound waves.
- I have produced and my invention includes as a separable element, an instantaneous varying light source of a most efficient character, highly actinic for photographic purposes and operable with comparatively low voltage, and peculiarly adapted for the production of a clear, distinct and readily translatable photograph of electrical variations, especially as effected by variations in sound waves.
- Other objects and advantages relate to the details of the apparatus, all as will more fully appear from the following description, taken in connection with the accompanying drawings, in which:—
- Figure 1 is a diagrammatic illustration of an embodiment of my invention.
- Figure 2 is a diagrammatic illustration of another embodiment of my invention.
- Figure 3 illustrates a somewhat different form of hook-up.
- The apparatus as shown comprises a microphone —1— connected in circuit with a source of potential, as battery —2— and the primary —3— of a transformer —4—, the secondary —5— of which is connected in circuit with the filament —6— and grid —7— of an electron-discharge device —8—, the plate —9— of which is connected in circuit with a source of potential, as battery —10—, the primary —11— of a transformer —12— and the filament —6— of the electron-discharge device.
- The filament —6— may be heated in any suitable manner, as by connection in circuit with the source of potential, as battery —24—. The secondary —13— of the transformer —12— is preferably connected in circuit with a source of potential, as battery —17— and the two spaced electrodes —14— and —15— disposed within the bulb —16— which may, perhaps, preferably be formed of glass with a quartz end through which the rays pass to the photographing apparatus.
- The electrodes may be of any desired form and as here illustrated, the electrode —14— is in the form of a comparatively small cylinder which may perhaps preferably be formed of a material such as aluminum to reduce the cathode sputtering and consequent darkening of the glass or quartz end-piece of the bulb —16—.
- Preferably the electrodes are arranged in close proximity, as for instance, a distance of about $\frac{1}{16}$ th to $\frac{1}{8}$ th of an inch, altho wide variation may be had in that respect.
- The essential feature of this invention resides particularly in the means provided for effecting operation of this bulb with comparatively low voltage, and further in the production of a variable light highly actinic for photographic purposes, and this is effected in accordance with the invention here disclosed by coating one or both of the electrodes with a rare earth oxide, such as thorium, cerium, etc., which materials in the combination here disclosed accomplish the object of this invention.
- My present experience leads me to believe that the advantages of this invention are attained by reason of the fact that the coating material consisting of or comprising a rare earth oxide as described, gives off electrons at room temperature under an impressed voltage whereby the operation of the lamp can be effected with comparatively low voltage in the production of a light highly actinic for photographic purposes, and the lamp is capable of carrying a much greater current when once in operation as compared with a lamp in which such a coating is not present. Also the character of the light is better.
- The bulb —16— should contain an easily ionizable gas, such as preferably helium, altho argon or other gases may be used, and by the expression "an easily ionizable gas", as used in the specification and claims hereof, I do not mean to limit myself to one particular character of gas, but rather use the expression as illustrative of any easily ionizable gas, whether it be of a single kind or character, or a combination or mixture of gases, as for instance, helium and argon.
- The light produced by the lamp of this invention is highly concentrated, and may, if desired, be made of very small size particularly desirable for photographic purposes when a lens —19— is used for focusing

the light upon a film —18— moving past the relatively small orifice —23— in the usual manner of photographing.

As before stated, the electrode —14— is here shown in the form of a small cylinder, as for instance $\frac{3}{8}$ ths of an inch in diameter, and preferably the interior only of the cylinder is coated with a rare earth oxide or oxides. The electrode —15— may perhaps 10 preferably, as shown, terminate near the base of the cylinder or may, if desired extend some distance into the cylinder.

In Figure 2 a structure is shown substantially similar to that illustrated in Figure 1, except that the electrode —15— is shown 15 in the form of a filament so that if desired, the same may be heated in any usual manner, as by a source of potential (not shown) or may be used as an unheated electrode in 20 the manner illustrated.

A structure similar to Figure 1 is illustrated in Figure 3 except that the transformer —12— is omitted and the electrodes —14— and —15— are connected directly in 25 circuit with the plate —9— and filament —6— of the electron-discharge device —8—.

As heretofore stated, it is my present opinion that the advantages of this invention are attained by reason of the fact that 30 one or both of the electrodes is coated with a rare earth oxide that gives off electrons under an impressed voltage, but the operation of this coating may be of some other character and may not be due entirely or 35 at all to the emission of electrons, and for that reason I do not desire to state positively the exact method of operation of the lamp, but limit my positive description to the fact that advantages are attained by 40 the apparatus as described without regard

to the particular reasons therefor, and I do not desire to limit myself to the form, shape or arrangement of the electrodes or any particular method of applying the coating of rare earth oxide or oxides, as various 45 changes may be made without departing from the invention as set forth in the appended claims.

I claim:—

1. In an apparatus for producing a photographic record of light variations corresponding to electrical variations, a bulb containing a pair of electrodes spaced apart a distance not greater than one inch, and the negative one of said electrodes comprising 50 a rare earth oxide, and a gas within the bulb at such a pressure that an intense concentrated glow is produced about the negative electrode.

2. In an apparatus for producing a photographic record of light wave variations corresponding to electrical variations, a bulb containing a pair of unheated electrodes in an atmosphere of an inert gas at such a pressure that a glow is concentrated about 55 the negative electrode at operating voltage, and the negative one of said electrodes comprising a rare earth oxide.

3. In an apparatus for producing a photographic record of light wave variations 60 corresponding to electrical variations, a bulb containing a pair of unheated electrodes in an atmosphere of helium at such a pressure that a glow is concentrated about the negative electrode at operating voltage, and the 65 negative one of said electrodes comprising a rare earth oxide.

In witness whereof I have hereunto set my hand this 26th day of March, 1923.

THEODORE WILLARD CASE.
